CRANK AND LEVER MECHANISM.

1,232,101.

Specification of Letters Patent.

Patented July 3, 1917.

Application filed February 2, 1916. Serial No. 75,823.

To all whom it may concern:

Be it known that we, HERMAN SCHWARTZ and ALFRED A. GRUNDY, citizens of the United States, residing at, respectively,

5 Philadelphia, county of Philadelphia, State of Pennsylvania, and Brooklyn, county of Kings, State of New York, have invented a new and useful Improvement in Crank and Lever Mechanism, of which the following is 10 a full, clear, and exact description; reference being had to the accompanying drawings, which form a part of this specification.

Our invention relates to flat or straight knitting machines. The object of our invention is to improve the mechanism for reciprocating the rods carrying the cam plates. Such mechanism usually comprises a crank pivoted at one end of the machine, a connecting rod pivotally connected with the 15 crank and extending to the other end of the machine, and a handle on the pivot between crank and rod; the rod being connected to a cross frame slidable on longitudinally extending fixed rods, and the rods carrying the cam plates being connected to the said frame.

The ordinary construction is open to several objections, among which may be mentioned the lack of capacity of adjusting the 20 length of the crank arm without producing excessive wear and tear at the bearing; the weakness of the connection between the crank arm and the connecting rod; and the side strain or twisting action of the cross frame upon the fixed rods upon which it slides. In the accompanying drawings is 25 shown a preferred embodiment of an invention adapted to overcome these defects.

Figure 1 is a plan view of a flat or straight 30 knitting machine embodying features of our invention. Fig. 2 is a front elevation of same. Fig. 3 is an end view of Fig. 2, enlarged. Figs. 4 and 5 are detail views of features of the invention.

40 The frame *a* of the machine carries the two end pieces *b* and *c* whose upper faces are beveled off to an angle of approximately 100 degrees with each other to adapt them to receive the needle beds. Longitudinally extending rails *d* and *e* are rigidly secured to the end pieces *b* and *c*. These rails are 45 grooved on their opposing sides to form guide-ways for the sliding cam plates *f* and *g* on the front and back of the machine.

Rods *h* connect the cam plates with a frame 55 *i* slidable on rods *j* arranged in parallel relation one above the other and rigidly secured to one end of the machine.

The cams are not shown, nor do we show the specific construction of the needle beds, 60 as these form no part of our invention. Nor is it necessary that the cam plates be supported or reciprocated precisely as described and shown.

We shall now proceed to describe that part 65 of the construction embodying our invention.

At the end of the machine opposite the frame *i* is a bracket *k*, in which turns a shaft 70 *l* carrying a head *m*. This head is cut away 75 diametrically along its axis to form a deep narrow slit shallow groove *n* which almost splits the head into two equal parts. An orifice *o* is cut through the head *m* in the direction of its diameter and parallel to the slit 80 *n* and in such manner that it intersects said slit, one half of the orifice being at one side of the slit and the other half at the other side of the slit. This orifice is shaped to receive the crank *t*.

Extending through the head *m* in the direction of its diameter and at right angles to the direction of extension of the orifice *o* is a hole *p*, one end of which is screw-threaded 85 while the other end is not.

The crank *t* is inserted in the orifice *o* and is adjusted therein so as to provide the desired length of crank. A pin *q* is inserted in the hole *p*. This pin is threaded at one end so as to have a screw-threaded engagement 90 in the hole. At the other end of the pin it is shouldered at *r* and provided with a handle *s*. By continuing to turn the pin *q* after its shoulder abuts against the head *m*, the two split parts of the head are forced toward 95 each other, thereby clamping the crank arm securely in the head.

The connecting rod *v* is provided with an offset sleeve *w*. Within this sleeve extends a pin *u* secured to the upper end of the crank 100 *t*. Thereby the bearing between the crank and connecting rod is lengthened and strengthened and the two members held in perfect alinement and prevented from twisting one upon the other.

A tubular handle *x* is slipped onto the bearing *w*. By means of this handle the operator reciprocates the connecting rod *v* and

the frame *i*, which is connected to the rod *v* by means to be now described.

Mounted on the frame *i* are two ears *y*, *y*. These ears are arranged directly above the 5 two shafts *j*, *j* (which are in vertical alinement) and on opposite sides of a plane coincident with the axes of both shafts. The rod *v* is bent inwardly and thence, at the end, longitudinally; this end extending between the ears *y*, *y* and being confined in place by a pin, bolt or the like extending through the ears and the end of the rod. 10 By this arrangement the back and forth pulling movement of the rod creates no twisting strain between the frame *i* and the connecting rod *v* or between the frame *i* and the rods *j*. The frame *i* and rods *j* are maintained in perfect alinement, causing the frame to slide upon the rods with a minimum 15 of friction. Thereby the power required to reciprocate the cam plates is reduced and the wear and tear of the plate minimized.

Having fully described our invention what 25 we desire to protect by Letters Patent is:

1. The combination with actuated mechanism, a crank arm, and a connecting rod between the crank arm and the actuated mechanism, of an oscillatory member split for part 30 of its length to divide it into two integrally connected halves, said member also provided with a crosswise orifice extending along opposite sides of said split and formed therefore partly in one half and partly in the 35 other half of said member, said orifice adapted to receive said crank arm, and means to clamp the two halves of the member to hold the crank arm in its adjusted position.

2. The combination with actuated mechanism, a crank arm, and a connecting rod between the crank arm and the actuated mechanism, of an oscillatory member split for part 40 of its length to divide it into two integrally

connected halves, said member also provided with a crosswise orifice extending along opposite sides of said split and formed therefore partly in one half and partly in the other half of said member, said orifice adapted to receive said crank arm, said member having a threaded hole extending across said 45 member through both halves thereof at one side of said orifice, and a threaded bolt extending through said hole and serving to clamp the two halves of said member upon the crank arm. 50

3. The combination with actuated mechanism and a connecting rod attached thereto, of an elongated handle sleeve fixed to the connecting rod, one end of the sleeve being in line with the end of the connecting rod 55 while the major length of the sleeve extends to one side of the connecting rod, a pivoted crank arm one end of which extends toward the other side of the connecting rod and an elongated pin on the crank arm extending 60 into said sleeve which affords a bearing therefor.

4. The combination with reciprocating mechanism of a connecting rod attached to said mechanism at approximately a point 70 on the longitudinal center line of said mechanism, said connecting rod thence extending outward and thence longitudinally alongside said mechanism, a pivoted crank arm, a pin 75 on the arm extending parallel to the axis on which the arm is pivoted and outwardly from said mechanism, and a sleeve fixedly secured to the connecting rod and adapted to receive and form an elongated bearing for said pin. 80

In testimony of which invention, we have hereunto set our hands, at Philadelphia, on this 28th day of January, 1916.

HERMAN SCHWARTZ.
ALFRED A. GRUNDY.
